[57] CLAIM

The ornamental design for a hand-held portable vacuum cleaner, as shown.

DESCRIPTION

FIG. 1 is a perspective view of a hand-held portable vacuum cleaner, showing my new design;

FIG. 2 is a left side elevational view thereof, the right side view being a mirror image;

FIG. 3 is a top plan view thereof;

FIG. 4 is a bottom plan view thereof;

FIG. 5 is a front elevational view thereof; and

FIG. 6 is a rear elevational view thereof.

Fig. 1.

Fig. 2.

FIG. 3.

FIG. 4.

FIG. 5.

FIG. 6.
